UNITED STATES PATENT OFFICE.

WILLIAM S. LODGE, OF ALBANY, NEW YORK.

LADY'S UNDERGARMENT.

No. 821,046.

Specification of Letters Patent.

Patented May 22, 1906.

Application filed March 16, 1905. Serial No. 250,344.

To all whom it may concern:

Be it known that I, WILLIAM S. LODGE, a citizen of the United States of America, and a resident of the city and county of Albany, State of New York, have invented certain new and useful Improvements in Ladies' Undergarments, of which the following is a specification.

My invention relates to ladies' undergarments constructed of knit goods; and the object of my invention is to provide a vest of knit goods so constructed that the garment shall be full in front. I accomplish this object by means of the mechanism illustrated in the accompanying drawings, in which—

Figure 1 is an elevation of a vest before being closed at the shoulders provided with my invention. Fig. 2 is a perspective view of a completed vest provided with my invention.

The vest A is preferably cut low in the neck, and the armholes B B for the sleeves are cut entirely out of the back, in order to

narrow the back and widen the bust portion of the garment, this arrangement causing all 25 the fullness of the garment to come to the front thereof. These garments are made on cylinder-frames. There is considerable give to the goods.

What I claim as my invention, and desire 30 to secure by Letters Patent, is—

1. A waist-garment, having the armholes cut entirely out of the back, in order to narrow the back and widen the bust portion of the garment.

2. A waist-garment, made from a tubular web, having the armholes cut entirely out of the back, in order to narrow the back and widen the bust portion of the garment.

Signed at Albany, New York, this 28th 40 day of February, 1905.

WILLIAM S. LODGE.
